UNITED STATES PATENT OFFICE.

JACOB PAYUCHECK, OF CHESTER, PENNSYLVANIA.

ADJUSTABLE WRENCH FOR MILLING-MACHINES.

1,392,025.

Specification of Letters Patent. Patented Sept. 27, 1921.

Application filed August 17, 1920. Serial No. 404,073.

To all whom it may concern:

Be it known that I, JACOB PAYUCHECK, a citizen of Russia, residing at Chester, county of Delaware, and State of Pennsylvania, have invented certain new and useful Improvements in Adjustable Wrenches for Milling-Machines, of which the following is a specification.

The present invention relates to a tool, particularly a wrench to be used in milling machines for removing the rotary knife or cutter head as a whole for the purpose of sharpening the knives or exchanging the cutter head.

It is a well known fact that in the art of milling that the removal of the rotary cutter head after its knives or blades once became dull could only be done by the destruction of the entire head by a chisel, hammer or the like.

It is the object of the invention to provide a tool by the use of which the cutter head of a milling machine can be removed from its cone-shaft, as a whole, without destroying any part of it and thus saving considerably on material, labor and expenses, and avoiding any considerable interruption in the operation of the machine.

The invention may be further briefly summarized as consisting in the construction and combination of parts hereinafter set forth in the following description, drawings and claims.

Referring to the drawings—

Figure 1 is a front view of the tool constructed according to the present invention looking toward the face of a milling machine.

Fig. 2 is a top plan view thereof.

Fig. 3 is an end view of the tool; parts being broken away to show the interior arrangement.

Fig. 4 is a sectional view, the section being taken on line 4—4 of Fig. 1.

Fig. 5 is a view similar to Fig. 1 with the cutter head in position to be operated upon by the tool according to the present invention.

Fig. 6 is a perspective detail view of one of the lugs used for binding the cutter head during the operation thereon of the tool.

In carrying out my invention, any preferred form and construction of parts may be employed, so long as they possess the necessary features, but I have shown one form in the drawings which meets the require-

ments with great efficiency; and in such embodiment, 10 represents one, and 11 the second jaw of the tool adapted for coöperation, and held together over the knives or blades 60 of a cutter-head by clamping screws 12 and 13 working in sockets 14 and 15 respectively pivotally secured to the lower jaw 10 by means of screw bolts 16 or the like. In order to allow an adjustment of the tool with 65 in certain limits to the various sizes of cutter heads the sockets 14 and 15 are provided with longitudinal front slots 17 in which screw bolts 18 screwed into the material of the upper jaw 10 are adjustable and can be 70 locked in their adjusted positions by means of the lock nuts 19 and washers 20. The lower as well as the upper jaw has its inner edge formed on substantially the arc of a circle and provided with offset shoulders 21 75 at substantially an angle of 70° to the jaws 10 and 11 corresponding to the angle of the knives 22 of a rotary cutter head 23 screwed upon the end of a cone-shaft 24 of a milling machine. The outer end of the upper jaw 80 11 is extended considerably beyond the socket 14, as indicated at 25 in order to constitute a lever by means of which the tool is operated.

As shown in Fig. 5, lugs of a form illustrated at 26 in detail in Fig. 6 are used to bind the cutter head and jaws as indicated at 27 in Fig. 5. The inner face of the shoulder and the inner face of the knife will form a straight surface for the reception and accommodation of the binding lugs.

In operation, the jaws of the tool are placed over the cutter head of a milling machine and after introduction of the lugs 26 between two of a plurality of knives in 95 several places, the jaws are clamped down upon knives and lugs in the well known manner. When now the shaft is started to rotate in a direction opposite to its rotation when operating the cutter head, and the extended lever 25 is chained down in any convenient manner, it will be clear that the cutter head will be removed from the cone shaft as a whole so that it can be exchanged for a new one while the blades or the knives 105 of the removed cutter head may be sharpened. It is clear that in this manner no noticeable interruption in the working of the machine will be necessary and that a considerable saving in labor, time and material is achieved.

Having thus described my invention,

what I claim, and desire to secure by Letters Patent of the United States is—

1. A tool of the character described comprising two clamp-jaws having their inner edges formed on the arc of a circle, shoulders on said inner edges, means for adjustably clamping said jaws over a rotary cutter head, and means coöperating with said shoulders for binding said cutter head and tool upon the reverse motion of the cone shaft for said cutter.

2. A tool of the character described comprising two clamp jaws having their inner oppositely disposed edges formed substantially on the arc of a circle, shoulders at the inner edges of said jaws, the outer ends of both jaws extended, sockets surrounding said extended outer ends, means for securing said sockets to the lower jaw, means for allowing a limited adjustment of the upper jaw with respect to the lower one, an operating lever on the upper jaw, and lugs engaging said shoulders adapted to be inserted between two of a plurality of pairs of knives of a rotary cutter head clamped between both jaws for binding jaws and knives upon the rotation of the shaft opposite to its working rotation.

3. A tool of the character described comprising two clamp-jaws, sockets for connecting both jaws pivotally secured to extensions of the lower jaw and secured to the upper

jaw, allowing an adjustment of the two jaws within certain limits, clamping screws entering said sockets from the top for locking both jaws in their adjusted relative positions, a lever extension on the upper jaw adapted to be chained down after the jaws have been clamped over the knives of a rotary cutter head, and means for binding said knives and cutter head upon the reverse rotation of the cutter head shaft.

4. A tool of the character described comprising two clamp-jaws each having a central part with its inner edge curved substantially on the arc of a circle for engagement with the knives or blades of a cutter head on the cone shaft of a milling machine, shoulders on the inner edges of both jaws substantially at an angle of 70° to said jaws corresponding to the arc of the cutters, lugs adapted to engage said shoulders and to be inserted between each pair of a plurality of knives and said jaws for binding both upon the rotation of the cutter shaft in a direction opposite to the cutter operating rotation, means for adjustably clamping both jaws over the cutters of a rotary head on the cone-shaft of a milling machine, and means for locking said jaws in their relative adjusted position over said head.

In testimony whereof I have affixed my signature.

JACOB PAYUCHECK.
